WILLIAM SHEPHERD, OF ROCHDALE, ENGLAND.

FILLER-BLOCK FOR STREET-RAILWAYS.

1,182,045.

Specification of Letters Patent.

Patented May 9, 1916.

Application filed March 24, 1915. Serial No. 16,726.

To all whom it may concern:

Be it known that I, WILLIAM SHEPHERD, a subject of the King of Great Britain and Ireland, residing at Sparthcliffe, Manchester 5 Road, Rochdale, in the county of Lancaster, England, contractor, have invented new and useful Improvements in Filler-Blocks for Street-Railways, of which the following is a specification.

10 In electric and other tramway systems it is now general to use a very heavy tramway rail of I or like section which presents a very considerable continuous cavity on each side of the rail as is well known. When 15 making good the road-way to such sections of rail, by laying granite sets to such rails, a somewhat difficult problem presents itself by reason of such continuous cavities. A common practice is to endeavor to plaster 20 up such continuous cavities with a mixture of tar and chippings, or, to fill up with some mixture containing cement and prepared on the spot. This making up of such cavities is known technically as "parging". Such 25 make shift methods of filling-in, are not however simple for workpeople to do and the job is apt to be scamped, and, even when properly done, the pitch melts under heat or the cement breaks under heavy vibration. 30 The result is, that such plaster masses crumble and fall away, or, are washed out of place, thus leaving the cavities unprotected, so that, sets which have settled down somewhat, or sunk, heel-over and get below the 35 flanges on the rail. Whenever such heeling over or falling away of sets occurs, then considerable portions of the upper parts of the rails are left exposed and become really dangerous projections, in particular 40 dangerous to the wheels of vehicles, or to pedestrians, and so sets in the immediate vicinity of tramway rails need constant and expensive attention.

Now my invention consists in the application 45 of continuous longitudinal lines of blocks or fillers which are solely applied to fill the cavities on each side of the rail and to lie entirely flush with the edges of the upper flange of the rail. I do not seek to isolate the rail at all, but, to apply absolutely flush continuous blocks to give a vertical wall up to the edge of the upper flange of the rail and to which the ordinary granite sets can be laid right up to the rail and 50 with the certainty of the line of granite sets maintaining their position and so that I can

dispense with the use of any mixture or "parging". The result is, that an exactly similar effect to set laying with "parging" is obtained, but with lasting qualities which 60 "parging" will not give, and, with this advantage, that the use of the blocks so facilitates the laying of the sets that the pavior for his own ease of working will always insert my filling blocks and so the immediate 65 continuous line of sets running longitudinally on each edge of the rail are the best held in the width of the sets.

I use a continuous line of abutting blocks which are so molded or shaped as to fit exactly flush with the edge of the upper flange of the rail and to occupy no more than the 70 existing cavity on each side of the rail.

The attached drawings illustrate my invention and the application of the ready 75 made blocks, sections, or the like, in connection with a tramway rail.

In such drawings: Figure 1 is a section showing one form of ready made block, section, or the like, in position filling-up exactly flush the continuous cavities. Fig. 2 shows a side elevation. Fig. 3 is a plan view, and Fig. 4 shows how the ready made blocks or sections can be made lighter and be provided with binding channels. Fig. 5 85 shows a block with inclined apertures down which pitch may pass to better bind the block in place.

I cut, mold, or otherwise produce, complete blocks, sections, tiles, or such like *a*, 90 and these may be of stone, slag, wood, fire or other clay, earthenware, stone-ware, or of other material or substance, and are of a depth and thickness to nicely occupy and fill up flush the continuous cavities between 95 the upper and lower flanges *a*¹ *a*² of the rail. The ready made blocks or sections are of suitable length, say about 9 inches, but this may be greatly varied. Such ready made blocks, or sections, abut end to end along 100 the continuous cavities and may be bedded on the bottom flanges on a thin layer of cement or pitch, but, more generally are simply laid in place but so as to produce a more or less truly vertical wall and a wall 105 flush with the edges of the upper flange as is obvious. This done, the sets *b* are laid upon the cinder or sand bedding *c*, over the concrete *d*, and right up to such truly vertical walls and so come against the solid abutment due to the presence of the ready made 110 blocks, or sections, which cannot give way

or escape, and so no set can heel over and get into the continuous cavity and produce a dangerous place in the road, the sets all along the lines standing squarely and truly 5 up to the rails.

In order that the ready made blocks or sections in a line may exercise a holding effect one on another when *in situ* I may bevel or incline or shape the vertical meeting edges, as I indicate in the lower part of Fig. 3. To lighten the ready made blocks or sections I may mold or produce the same with passageways, channels, or even holes. Likewise, I might have channels or grooves 15 formed in the blocks or sections, into which pitch or cement could pass to produce a better joint along the meeting wall of the sets with the ready made blocks or sections or between the ready made blocks or sections 20 and rail. Also, the vertical meeting edges of the ready made blocks or sections might be channeled or grooved so that the running down of pitch, or such like in finishing off the road, would interlock a line of the 25 applied ready made blocks or sections. These several detail features are shown by Fig. 4. In Fig. 5 I indicate the use of holes or channels disposed at an angle in the block or sections *a*.

30 I declare that what I claim is:

1. A block adapted to fit between the tread and base flanges of a track rail at one side of the rail web and having its outer side face parallel with the opposite side face 35 and adapted to lie flush with the corresponding side face of the rail tread, and means provided at each end of the block by which it may be interlocked with the adjacent end of a co-acting block.
- 40 2. A block adapted to fit between the tread and base flanges of a track rail at one side of the rail web and having its outer side face parallel with the opposite side face and adapted to lie flush with the corresponding side face of the rail tread, the 45

ends of the block being cut to provide projecting corner portions by which the said ends may be interlocked with the adjacent ends of co-acting blocks.

3. A block adapted to fit between the 50 tread and base flanges of a track rail at one side of the rail web and having its outer side face parallel with the opposite side face and adapted to lie flush with the corresponding side face of the rail tread, each end of the 55 block being beveled transversely substantially as and for the purpose described.

4. A block adapted to fit between the tread and base flanges of a track rail at one side of the rail web and having its outer 60 side face parallel with the opposite side face and adapted to lie flush with the corresponding side face of the rail tread, the ends of the block being oppositely beveled transversely, substantially as and for the purpose described. 65

5. A block adapted to fit between the tread and base flanges of a track rail at one side of the rail web and having its outer side 70 face parallel with the opposite side face and adapted to lie flush with the corresponding side face of the rail tread, the block being provided with a transverse pouring opening.

6. A block adapted to fit between the tread and base flanges of a track rail at one 75 side of the rail web and having its outer side face parallel with the opposite side face and adapted to lie flush with the corresponding side face of the rail tread, the block being provided with a transverse pouring opening 80 which is inclined downwardly toward the inner face of the block.

In testimony whereof I have signed my name to this specification in the presence of two subscribing witnesses.

WILLIAM SHEPHERD.
